(57) **CLAIM**

I claim the ornamental design for a correction tape dispenser, as shown and described.

DESCRIPTION

FIG. 1 is a front perspective view of a correction tape dispenser of the present invention.

FIG. 2 is a top plan view thereof.

FIG. 3 is a front view thereof.

FIG. 4 is a left side view thereof.

FIG. 5 is a right side view thereof.

FIG. 6 is a bottom plan view thereof; and, FIG. 7 is a rear view thereof.
